UNITED STATES PATENT OFFICE.

WILLIAM H. RICHMOND, OF MOUNT PLEASANT, MICHIGAN.

FOLDING BOX.

No. 823,810.

Specification of Letters Patent.

Patented June 19, 1906.

Application filed March 7, 1905, Serial No. 248,824.

To all whom it may concern:

Be it known that I, WILLIAM H. RICHMOND, a citizen of the United States of America, residing at Mount Pleasant, in the county 5 of Isabella and State of Michigan, have invented certain new and useful Improvements in Folding Boxes, of which the following is a specification, reference being had therein to the accompanying drawings.

10 This invention relates to a folding box of that character in which the parts are all connected together by hinge-joints in such manner as to permit the box to be folded into a smaller compass for making it more convenient to ship when empty; and the invention consists in the novel manner of hinging the parts together, whereby the invention is applicable to boxes of cubical shape and in a manner whereby the use of special fittings is 15 wholly avoided, all as more fully hereinafter described, and shown in the accompanying drawings, in which—

20 Figure 1 is a perspective view of my box in a partially knockdown position of the parts.

25 Fig. 2 is an elevation of the box as it appears when fully knocked down and ready for shipping. Figs. 3 and 4 are cross-sections of the completed box in planes at right angles to each other, and Fig. 5 is a horizontal section.

30 A is the bottom.

B is the front side.

C is the rear side.

D and E are the ends, and F is the cover.

The front and rear sides are respectively 35 hinged directly to the front and rear edges of the bottom A, the latter by inside hinges *a*, adapting it to be folded upon the upper side of the bottom, and the former by outside hinges *b*, adapting it to be folded against the 40 under side of the bottom.

One of the two ends—say the end D—is hinged directly to the front side B by inside 45 hinges *c*, while a portion E' of the other end is fixedly secured to the front side B; and the other portion is hinged to it by inside hinges *d*, all in such manner that it may fold upon the end D, as shown in Fig. 2. The ends D and E are also formed at their free vertical edges with rabbets *f*, adapted to receive the 50 ends of the rear side C, as shown.

The cover F is hinged by outside hinges *e* to the top of the rear side and can be folded freely against the outer face of the rear side. This cover is provided with a depending edge

strip G, adapted to shut down over the top 55 of the ends and the front of the box.

With this construction of the parts the box can be knocked down in a very obvious manner, the parts folding upon each other, as shown in Fig. 2, and it will be seen that the 60 parts lie close and compactly together and occupy less than one-third of the space of the box.

It will be noticed that if the cover is closed and fastened down by a suitable nail or screw 65 *m*, as shown in Fig. 3, it interlocks with the sides and ends, and the box holds together without the use of any other fastening; but of course additional fastenings may be used to strengthen the box, if necessary. I prefer 70 to use screws for the purpose, and these screws I make to perform a double service—as, for instance, by using a screw *g* in each end board these screws may serve to secure the end boards to the bottom A in putting 75 the box together, and in knocking down the box they may be screwed out just enough to allow the parts to come apart and then in folding be screwed in again in the new position of the parts, as shown in Fig. 2, when 80 they perform the function of holding the parts together in their folded position, and thus making a tight bundle of the whole.

My construction is especially devised for boxes which are more or less of cubical shape, 85 which shape requires the least amount of lumber for a given cubical contents, and it will also be observed that the interior of the box is wholly unobstructed, and there is also an advantage in the way the cover-plate 90 folds, since the outside, which may carry the shipping-address, is hidden when folded, while the inside is exposed when folded, and thus the two destinations between which the box is used may be permanently carried on 95 the cover.

Having thus fully described my invention, what I claim is—

In a folding box having a hinged cover, of a bottom and front and rear members hinged to the bottom by outside and inside hinges adapting them to fold respectively against the under and upper faces of said bottom, and end members, one of which is hinged by inside hinges to the front member adapting 100 it to fold flat against said member and the other one of which is correspondingly hinged to a complementary portion thereof, which is 105

rigidly secured to the front member adapting said end member to fold flat upon the other end member—the box being of cubical shape—said front, rear and end members being of uniform height and extending with their lower edges over the outer edges of the bottom member and adapted to be held in rigid relation to each other by screws passing

through the end members into the bottom member.

In testimony whereof I affix my signature in presence of two witnesses.

WILLIAM H. RICHMOND.
